DESCRIPTION

U.S. PATENT DOCUMENTS

FIG. 1 is a first perspective view of a head for golf club;

D382,616 S * 8/1997 Heffley D21/749
D456,056 S * 4/2002 Bakke D21/747
D470,554 S * 2/2003 Truesdale D21/747
D490,490 S * 5/2004 Gilbert et al. D21/759
D549,791 S * 8/2007 Morris et al. D21/748
D559,931 S * 1/2008 Roach et al. D21/747

FIG. 2 is a second perspective view thereof;

FOREIGN PATENT DOCUMENTS

FIG. 3 is an elevational view thereof;

JP	1062771	3/2000
JP	1077587	7/2000
JP	1150632 S	8/2002
JP	1159079 S	11/2002
JP	1199297 S	3/2004
JP	1259983 S	1/2006

FIG. 4 is a left side view thereof;

FIG. 5 is a right side view thereof;

FIG. 6 is a top view thereof; and,

FIG. 7 is a bottom view thereof.

The portion shown by broken lines is for illustrative purposes only and forms no part of the claimed design. The dashed lines show a borderline between the claimed design and other portion.
